UNITED STATES PATENT OFFICE.

RAYMOND E. CRANE, OF CAMERON, WEST VIRGINIA.

DESIGN FOR A LAVATORY-BOWL.

40,401.

Specification for Design.

Patented Dec. 14, 1909.

Application filed December 22, 1908. Serial No. 468,875. Term of patent 14 years.

To all whom it may concern:

Be it known that I, RAYMOND E. CRANE, a citizen of the United States, residing at Cameron, in the county of Marshall and State of West Virginia, have invented a certain new, original, and ornamental Design for Lavatory-Bowls, of which the following is a specification, reference being had to the accompanying drawing, forming part thereof.

In the drawing, Figure 1 is a top plan view of the bowl, and Fig. 2 is a front elevation of the same.

The lavatory is made of circular shape comprising an integral bowl and a slab, said slab having a marginal rim extending above and below the edge thereof, the lower por-

tion of said rim forming an apron, the upper portion of said rim at the rear of the lavatory being extended upwardly to form a curved back, relatively high at its central portion and gradually merging into the rim at its sides. The basin part of the bowl extends below the slab to approximately the same extent that the back rises above the same.

I claim:—

The ornamental design for a lavatory bowl, as shown and described.

RAYMOND E. CRANE.
